HINGE CONSTRUCTION

Oscar E. Norberg, Cincinnati, Ohio, assignor, by
mesne assignments, to Gibson Refrigerator
Company, Greenville, Mich., a corporation of
Michigan

Application June 25, 1941, Serial No. 399,648

1 Claim. (Cl. 16—131)

1 Broadly, this invention relates to refrigerators. More specifically, it relates to closure members for evaporator chests and the like, and to novel means for pivotally supporting the closure member.

Heretofore, closure members for the access opening of evaporator chests and the like have been pivotally supported directly from the chest and arranged when closed to directly contact the chest. Such constructions have not been entirely satisfactory because the closure members become frozen to the evaporator chest and cannot be easily opened. When the closure member is made of glass, either with or without a metal frame, the close proximity of the glass to the chest causes objectionable condensation on the glass.

Accordingly, the principal object of the invention is to provide a closure member for the access opening of an evaporator chest which is spaced from the chest and thereby avoid the possibility of the closure becoming frozen to the chest; and in the case of glass closures, to minimize the deposition of vapors on the glass.

In spacing the closure member from the chest, a problem is presented as to how to support the closure member. The natural solution is to support it from the liner of the storage compartment in which the chest is located. This presents a further problem when providing a closure member for access openings extending substantially from one wall to another of the storage compartment. In that case, the closure member must span substantially the entire space from one liner wall to another. Consequently, conventional hinge or pivot mountings cannot be used because of the difficulty in assembling the closure member after the cabinet structure has been completed.

Accordingly, a secondary object of the present invention is to provide a mounting for closure members which extends from one liner wall to another, whereby the closure is pivotally supported from the two walls and can be readily mounted and dismounted, without fear of accidental dislodgement of the closure from its installed position.

The foregoing objects and others ancillary thereto will more fully appear in the following specification when read in connection with the accompanying drawings, wherein—

Figure 1 is a front elevational view of a refrigerator embodying the invention, the door of the refrigerator being open to show the interior construction thereof;

Figure 2 is a fragmentary cross-sectional view taken on substantially the line 2—2 of Figure 1;

2 Figure 3 is a fragmentary cross-sectional view taken on substantially the line 3—3 of Figure 1;

Figure 4 is a fragmentary front elevational view of the closure for the evaporator chest and a portion of the liner of the food storage compartment; and

Figure 5 is a fragmentary cross-sectional view taken on substantially the line 5—5 of Figure 3.

The invention is shown as applied to a refrigerator of the household type. The refrigerator comprises a cabinet which consists of an outer casing 10 and an inner liner spaced from the outer casing and defining a food storage compartment 11. The inner liner of the food storage compartment includes a pair of oppositely disposed upright side walls 12. The food storage compartment is provided with a door 13. Within the food storage compartment 11 and supported upon the upright walls 12 are a number of shelves 14.

In the top of the compartment 11 is an evaporator chest 15 which is supported from the top wall, is spaced from all of the walls, and extends substantially from one side wall to the other side wall. The evaporator chest 15 comprises a metal housing, shown best in Figures 3 and 4, open at its front side. The evaporator chest is cooled by an evaporator coil, such as the sinuous coil of tubing 15a wrapped about the housing. The evaporator chest is adapted to contain ice cube trays or other containers for frozen articles.

The open front side of the evaporator chest is provided with a closure 16, which is spaced from the chest throughout its entire extent. The closure preferably is made of a sheet of glass. The glass sheet is reinforced and supported about its edges with a narrow metal frame 17 of channel-shaped cross-section. The glass plate is suitably ornamented at 18 and has a handle 19 attached to the frame 17 at its upper edge.

Instead of being hinged on the evaporator chest, as has been the custom heretofore, the closure 16 is pivotally connected on a horizontal axis adjacent its lower edge directly to the upright side walls 12 of the storage compartment 11. The closure 16 is adapted to swing from a vertical closed position (see Figure 2) to a horizontal open position wherein it is adapted to act as a shelf for a temporary support for articles which are to be removed or inserted into the evaporator chest. The novel pivot construction for the evaporator chest is designed to permit such use of the closure. Furthermore, since it is impossible to gain access to the outside of the liner of the food storage compartment after it has been assembled in the

cabinet, the pivot construction is such as to permit assembly and disassembly of the closure from the liner from within the food storage compartment. The particular pivot construction will now be described.

A pair of generally triangular plates 20 are attached to the frame 17 of the closure at its opposite ends. The plates 20 extend at right angles to the plane of the closure 16, and are provided with flanges 21 at their front edges which are secured to the frame 17 by means of screws 22. The plates 20 have short extensions 23 at their upper front and lower rear corners for a purpose which will appear presently. A hole 24 for the reception of a hinge pin is formed in the lower front corner of each of the plates 20. Still another hole 38 for the reception of one end of a spring, which will be described later, is also provided in each plate 20.

In each side wall 12 of the storage compartment and aligned with the hole 24 in the adjacent plate 20 is a hole 26. A sleeve 27 having a portion 28 of a diameter slightly less than that of the hole 26, and an inner end portion 29 of considerably greater diameter, is positioned with the portion 28 in the hole 26. The portion 28 of the sleeve is both internally and externally threaded. A speed nut 30 cooperates with the external threads of the portion 28 to secure the sleeve 27 to the side wall 12.

A hinge pin having an externally threaded shank 31 is threaded into the portion 28 of the sleeve. The hinge pin has a head 32 of a diameter substantially that of the hole 24 in the plate 20 and is inserted therein. The head 32 is slotted at 34 for the reception of a screw driver whereby to adjust the hinge pin. Between the head 32 and the shank 31 is an enlarged shoulder 33 which is adapted to engage the outside face of the adjacent plate 20 to position the closure laterally of the storage compartment 11.

A torsion spring 35 is wound around the enlarged portion 29 of the sleeve 27. The ends of the spring 35 extend rearwardly and their extremities are bent to form hooks 36 and 37. One hook 36 is inserted in the hole 25 in the wall 12, while hook 37 is inserted in a corresponding opening 38 in the adjacent plate 20. The spring 35 is always under some stress and tends to urge the closure 16 to its closed position.

In order to conceal the spring 35, the sleeve 27 and their associated parts, a cover 39 is provided. This cover is semi-circular in elevation (see Figure 2). It is secured to the corresponding wall 12 and in front of the parts of the pivot for the closure by means of screws 40.

Secured to the wall 12 directly above the hinge pin is a stop pin 41. The inner end of the stop pin projects inwardly past the plane of the adjacent triangular plate 20 and cooperates with the lugs 23 to limit the movement of the closure 16. It will be noted from an inspection of Figure 2 that the upper front lug 23 strikes the stop pin 41 when the closure 16 is shut, and the lower rear lug 23 contacts the stop pin 41 when the closure is in its open position. Thus, the shelf is properly supported in its horizontal position, and the closure is spaced slightly from the evaporator chest 15 when the closure is in its vertical closed position. Damage to the closure or to the evaporator chest when the closure is permitted to slam shut, is effectively prevented by a resilient sleeve 42 of rubber or similar material which encases the stop pin 41 and cushions the shock of contact between the pin 41 and the lugs 23.

The structure just described is very easily as-

sembled and disassembled. Preferably in manufacturing the refrigerator cabinet the sleeves 27 are secured to the side walls 12 of the liner by the nuts 30 prior to assembly of the liner within the cabinet. The stop pins 41 should also be secured to the liner prior to assembly in the cabinet. The rest of the closure and its pivot connection can be made after the cabinet is completed. The last mentioned assembly is effected by inserting the pivot pins into the sleeves 27 and threading them laterally outwardly a sufficient distance to permit the insertion therebetween of the closure 16 and the plates 20 which are secured thereto. The spring 35 is placed over the enlarged part 29 of the sleeve and the hook 36 inserted in the opening 25 in the side wall 12. Then the cover 39 may be secured to the side wall 12. The closure 16 is then inserted into the cabinet between the heads of the pivot pins, and a screw driver is inserted through the hole 24 and into the slot 34 in the head of the pivot pin, and the pivot pin backed out so that its head 32 extends into the hole 24 and the shoulder 33 engages the plate 20.

From the foregoing, it will be seen that the present invention overcomes the difficulties of the prior art, and provides a novel and extremely simple construction for pivotally mounting a closure member within a storage compartment of a refrigerator cabinet.

30 The scope of the invention is indicated in the appended claim.

I claim:

A device of the character described comprising a fixed supporting member, a hinge member spaced from said fixed supporting member, an internally threaded sleeve having an end secured to said fixed supporting member and its other end positioned between said supporting member and said hinge member, said last named end being of substantially greater diameter than said first named end, a torsion spring surrounding the enlarged end of said sleeve and having one end connected to said hinge member and the other end connected to said supporting member, and a hinge pintle, said hinge pintle having a shank end threaded into said sleeve and axially adjustable relative thereto, said hinge pintle having a head end extending through an opening in said hinge member and having an annular shoulder thereon 50 engaging said hinge member.

OSCAR E. NORBERG.
